UNITED STATES PATENT OFFICE.

GEORGE BEDFORD, OF TORONTO, ONTARIO, CANADA.

REGISTERING DEVICE FOR PLAYER-PIANO MUSIC ROLLS.

Application filed June 23, 1921. Serial No. 479,918.

To all whom it may concern:

Be it known that I, GEORGE BEDFORD, of the city of Toronto, in the county of York, Province of Ontario, Canada, a subject of the King of Great Britain, have invented certain new and useful Improvements in Registering Devices for Player-Piano Music Rolls, of which the following is a specification.

10 This invention relates to means for positioning the music rolls of player pianos so that the perforations in the music are properly alined with the apertures in the tracker bar, and my object is to devise mechanical 15 means for automatically centering the rolls to compensate for the variations in the width of the rolls which are commonly found.

20 I attain my object by means of the constructions hereinafter described and illustrated in the accompanying drawings in which

25 Fig. 1 is a front elevation, partly in section, of part of a player piano action constructed in accordance with my invention;

Fig. 2 a plan view of the same; and

30 Fig. 3 a diagrammatical view of a slight modification illustrating the mode of operation of the device.

35 In the drawings like numerals of reference indicate corresponding parts in the different figures.

1 is that part of the frame of a player piano action which supports the tracker bar, 35 the rollers for the music, and the operating mechanism therefor. 2 is the tracker bar and 3 the roller on to which the music is wound from the original roll. This roller being of ordinary construction and mounted 40 in the ordinary manner requires no detailed description.

45 Mounted in one side of the frame is a trunnion 4 having its inner end 5 adapted for detachable engagement with one end of the roller of a music roll in the ordinary manner. This trunnion is freely slidable lengthwise of the frame and is provided with the usual brake drum 6, which serves also to limit the inward movement of the trunnion.

50 The trunnion 7 for the other end of the roller is mounted to rotate in a sliding member 8, which is movable longitudinally in the side of the frame 1. The trunnions therefore are free to rotate and also to move axially of the roller 3.

Means are provided whereby movement of one trunnion longitudinally imparts the same amount of movement in the opposite direction to the opposite trunnion. This result is attained by means of the following mechanism. The lever 9 is fulcrumed intermediate its ends adjacent the trunnion 7 and is connected at one end by means of the pivoted link 10 to a collar 11 clamped on the 60 sliding member 8. Adjacent the trunnion 4 is a lever comprising two arms 12 and 13 and the spindle 14 with which they are connected. The spindle is journalled in brackets 15 secured to the frame 1. The arm 13 65 is engaged with the end of the trunnion 4. A connecting rod 16 is pivotally connected with the levers so that the movement of the lever is reversed, the lower end of the lever 9 moving to the left when the arm 13 moves 70 to the right and vice versa.

75 In order that the positions of the levers may be adjusted to ensure the centre of the roller being in exact alinement with the centre of the tracker bar, means are provided 80 for varying the effective length of the link. This is conveniently effected by threading the end 17 of the connecting rod 16 and screwing it through a pin 18 rotatably mounted on the arm 12. A spring 19 is 85 employed tending to move one of the trunnions inwardly towards the centre of the tracker bar. This spring is preferably directly engaged with the sliding member 8 and bears against a shoulder 20 formed 90 thereon and a shoulder within the shell 21 secured to the frame and through the outer end of which the sliding member slides. The roller is thus easily placed in position by engaging the proper end of the roller 95 with the trunnion 4 and pushing the roller towards the right. The trunnion 7 then moves back, due to the lever and linkage connection described, and the roller is readily brought into position and the trunnion 100 allowed to engage in its end under the action of the pressure of the spring.

105 The action of the device will be more readily seen by a consideration of the modification shown in Fig. 3. In this form each trunnion 22 is shown slidable directly in the frame, and a roller 23 is shown engaged between them. A lever of the first order shown at one side directly engages the end of the trunnion at that side, while a 110 lever of the third order is shown as directly engaging the trunnion 22 at the opposite

side. A connecting rod 25 is shown connected to the opposite end of the lever 24 to that which engages the trunnion, while this connecting rod is pivotally connected 5 with the lever 27 at a point intermediate its fulcrum and its point of engagement with the trunnion at that side.

A coil spring 26 engages the lever 24 and a stationary part and operates in the same 10 manner as the spring 19 shown in Fig. 1.

It will be found with my construction that no matter what irregularities may exist in the length of the rollers that the excess or deficiency in length will always be 15 accurately divided between the two trunnions so that the actual middle of the roller will always aline accurately with the centre of the tracker bar. Troublesome and expensive pneumatic alinement devices may thus 20 be dispensed with, while the present device, being automatic, is much superior to the manual adjustments sometimes provided.

What I claim as my invention is:—

1. In player piano actions, the combination of a frame; a trunnion journalled in the frame; a member slidably supported at the opposite side of the frame in axial alinement with said trunnion; a trunnion journalled on said slidable member, said trunnions being adapted to receive a music roll between them; a link pivotally connected to said sliding member; a lever of the first order fulcrumed on a stationary part pivotally connected at one end to said link; a spindle journalled adjacent the first mentioned trunnion; an arm on the spindle engaging the outer end of the trunnion; a second arm connected to the spindle and extending in the same direction as the first mentioned arm; a connecting rod pivotally connected to the said arm and the end of the lever remote from the link; and a spring tending to press the trunnions towards one another.
2. In player piano actions, the combination of a frame; a trunnion journalled in

the frame; a member slidably supported at the opposite side of the frame in axial alinement with said trunnion; a trunnion journalled on said slidable member, said trunnions being adapted to receive a music roll between them; a link pivotally connected to said sliding member; a lever of the first order fulcrumed on a stationary part pivotally connected at one end to said link; a spindle journalled adjacent the first mentioned trunnion; an arm on the spindle engaging the outer end of the trunnion; a second arm connected to the spindle and extending in the same direction as the first mentioned arm; a connecting rod pivotally connected to the said arm and the end of the lever remote from the link; and a spring engaging the sliding member and a stationary part and tending to press the trunnions towards one another.

3. In player piano actions, the combination of a frame; a trunnion journalled in the frame; a member slidably supported at the opposite side of the frame in axial alinement with said trunnion; a trunnion journalled on said slidable member, said trunnions being adapted to receive a music roll between them; a link pivotally connected to said sliding member; a lever of the first order fulcrumed on a stationary part pivotally connected at one end to said link; a spindle journalled adjacent the first mentioned trunnion; an arm on the spindle engaging the outer end of the trunnion; a second arm connected to the spindle and extending in the same direction as the first mentioned arm; a connecting rod pivotally connected to the said arm and the end of the lever remote from the link; means for varying the effective length of said connecting rod; and a spring tending to press the trunnions towards one another.

Signed at Toronto, Canada, this 15 day of June 1921.

GEORGE BEDFORD.
